UNITED STATES PATENT OFFICE.

JOHN W. PAX, OF CHICAGO, ILLINOIS.

DESIGN FOR A HOLDER.

SPECIFICATION forming part of Design No. 33,452, dated October 30, 1900.

Application filed October 2, 1900. Serial No. 31,792. Term of patent 7 years.

all whom it may concern:

Be it known that I, JOHN W. PAX, a citizen of the United States, residing at Chicago, in the county of Cook and State of Illinois, have 5 invented and produced a new and original Design for Holders; and I do hereby declare the following to be a full, clear, and exact description of the same, reference being had to the accompanying drawing, forming a part o thereof.

This invention relates to a new and original design for a holder for pencils, pens, and like articles.

As shown in the accompanying drawing, 5 the design comprises a flat substantially rectangular-shaped member A, connected by a return-bend C with a second substantially rectangular-shaped member B. The member B extends from the return-bend C upwardly and o inwardly to approximately a point about two-thirds the height of the member A.

D represents a series of slits or spaces separating the upper portion of the member B, as shown, into somewhat-elongated strips F, which at their extreme end are turned outwardly and around, as at E.

The essential features of the design are the two members A and B, bent so as to approach each other, and the separated strips on one of said members.

Having thus described the invention, what is claimed as new, and desired to be secured by Letters Patent, is—

The design for a holder, substantially as shown and described.

In testimony whereof I affix my signature in presence of two witnesses.

JOHN W. PAX.

Witnesses:

GEORGE E. TEW,
WM. J. ROBINSON.
